COMBINED CIGAR PACKAGE AND DISPLAY UNIT

John A. Dreher, Trucksville, Pa., assignor to General Cigar Co., Inc., New York, N.Y., a corporation of New York

Filed July 22, 1960, Ser. No. 61,492

Term of patent 14 years

(Cl. D58—2)

FIG. 1

FIG. 1 is a front elevational view of a combined cigar package and display unit, showing my new design; FIG. 2 is a side elevational view thereof; and FIG. 3 is a rear elevational view thereof. The side not shown is the same as the side shown. I claim: The ornamental design for a combined cigar package and display unit, substantially as shown and described.
